Term of patent 14 years

Int. Cl. D17—01

U.S. Cl. D56—9

FIG. 1 is an angular perspective view of a piano case embodying my new design.

FIG. 2 is a side elevational view; and

FIG. 3 is a front perspective view thereof.

The side of the piano case not shown is the same as the side shown.

The back, not shown, is conventional, and the conventional keyboard fragmentarily shown by means of solid lines is continuous across the piano as indicated by the long dash dot lines.

I claim:

The ornamental design for a piano case, substantially as shown and described.
